UNITED STATES PATENT OFFICE

108,044

DESIGN FOR A GARDEN TOOL

Wayne Washington Wallace, Harriman, Tenn.

Application August 28, 1936, Serial No. 64,625

Term of patent 14 years

To all whom it may concern:

Be it known that I, Wayne Washington Wallace, a citizen of the United States, residing at Harriman, in the county of Roane and State of Tennessee, have invented a new, original, and ornamental Design for a Garden Tool, of which the following is a specification, reference being had to the accompanying drawing, forming part thereof.

Figure 1 is a rear perspective view of a garden tool, showing my new design; and

Figure 2 is a front perspective view thereof.

The characteristic feature of my design resides in the symmetrical location of the two innermost tines of the forked portion of the tool, spaced equidistant at opposite sides of the major axis of the tool head and relatively shorter than the outermost tines with a U-shaped base for the innermost tines extending from the neck portion of the tool.

I claim:

The ornamental design for a garden tool, as shown, and described.

WAYNE WASHINGTON WALLACE.
